CHANGE-SPEED MECHANISM FOR
PHONOGRAPH DRIVES

Marcel Jules Helene Staar, 30 Square du Solbosch,
Brussels, Ixelles, Belgium

Filed Oct. 24, 1957, Ser. No. 692,187

Claims priority, application Belgium Mar. 22, 1957

16 Claims. (Cl. 74—200)

This invention relates to plural speed turntable drives for phonograph apparatus, and more particularly to a type of drive employing a stepped drive roller, and an idler wheel positionable so as to be drivingly engaged between the turntable flange and the surface of one of the steps of the drive roller.

It is a primary object of the present invention to provide a turntable drive of this type in which, by means of a change-speed mechanism, the idler is shiftable between the steps of the driver roller to obtain a desired speed, and, as well, to a declutched or zero position where the idler is free from peripheral contact with the turntable flange and drive roller to prevent the development of flat spots during periods of non-use of the apparatus. A further object of this invention is to provide for manual shifting of the idler wheel through movement of a manually operable control handle.

Heretofore in turntable drives of this type, it has been the usual practice to mount the idler wheel such that it may be cammingly moved:

(1) Vertically for raising and lowering the idler between the levels of the steps of the drive roller; and

(2) Laterally to clear each roller step. Thus when the idler wheel moves to obtain different speeds it is free from contact with the drive roller. While such arrangements are, in general, satisfactory, the presence of cams and associated elements to produce this idler wheel movement renders the change-speed mechanism complex, resulting in increased initial costs, servicing difficulties, and a greater tendency to mechanical failure.

It is now proposed to reduce the complexity of the mechanism and improve the operation by moving the idler wheel so that it partakes of a different action, wherein it remains in contact with the drive roller while changing speeds. Accordingly, it is an object of the invention to provide for sliding the idler wheel from step to step of the drive roller in the direction of decreasing roller step diameter, i.e., in the direction from high turntable speed to low turntable speed. It is a related object to carry out this sliding action of the idler wheel upon forward movement of a manual control lever, and while the idler wheel remains under the direct control of the operator during each successive speed changing movement.

It is a further object to provide for shifting the idler wheel manually from engagement with the smallest diameter roller step and by spring actuated means to move the idler wheel directly to the zero position. It is a related object to provide spring operated means for shifting the idler wheel, which means acts independently of the manually controlled means once it is actuated, upon reverse movement of the manual control lever.

Other and additional objects will appear from the following description taken in connection with the accompanying drawings, wherein:

Figure 1 is a perspective view of the plural speed turntable drive mechanism embodying the present invention;

2

drive mechanism positioned to engage the idler wheel with the smaller step of the drive roller;

Fig. 3 is an enlarged fragmentary perspective view of a portion of the drive mechanism;

5 Fig. 4 is another stop motion view, like Fig. 2, but with the parts of the drive mechanism positioned with the idler wheel in the zero position;

Fig. 5 is a fragmentary sectional view taken substantially in the plane of lines 5—5 of Fig. 3;

10 Fig. 6 is a top plan elevational view of the drive mechanism in the low speed position;

Fig. 7 is a top plan elevational view showing the drive mechanism with the manual control lever shifted toward the zero position; and

15 Fig. 8 is a top plan elevational view showing the drive mechanism with the parts in the zero position.

While the invention is susceptible of various modifications and alternative constructions, there is shown in the drawings and will be described herein in detail an illustrative embodiment of the invention. But it is to be understood that it is not thereby intended to limit the invention to the specific form disclosed, and it is intended to embrace all modifications, alternative constructions and equivalents falling within the spirit and scope of the 25 invention as expressed in the claims.

Referring to the drawings, there is shown in Figure 1 a record turntable 10 operated by a speed drive mechanism. The turntable is driven from a motor shaft 12 on which there is mounted a stepped drive roller 13, having, 30 in the present instance, four separate steps for providing turntable speeds of 16, 33 1/3, 45 and 78 r.p.m., to play standard records. Interposed in drive relation between a flange 14 depending from the turntable and the stepped drive roller 13, is an idler wheel 15 which is shiftable by 35 means of a change-speed mechanism from a zero position, as depicted in Fig. 4, into engagement with the larger roller step and successively into engagement with the smaller steps of the roller 13 to obtain a selected turntable speed. To facilitate this movement, the change-speed mechanism 40 provides a floating mount 17 for the idler wheel 15, having an arm consisting of pivotally joined links 19, 20 mounted for movement horizontally, and vertically slidable on a pin 22 fixed to the base of the player. The connection between the links 19, 20 is provided by the pin 23. At one end of the floating mount 17, the idler wheel is rotatably mounted on the shaft 24. In the present instance the idler wheel when positioned in driving relation, is wedged between the stepped drive roller 13 and the turntable flange 14, being yieldably held in engagement with the roller and the turntable by means of a tension spring 25.

To carry out the appropriate positioning of the idler wheel in order to obtain a desired turntable speed, a manually operated handle 30 is provided for operating 55 the change-speed mechanism, in the present case this handle being fixed to a horizontal actuating shaft 31 (Fig. 5) rotatably mounted on the player base by means of a bracket 31' or the like. The handle 30 is arranged to control separate actuating means for the idler wheel mount 17, both of which means are embodied in the change-speed mechanism. The first of these actuating means is employed for shifting the idler wheel mount vertically, and by virtue of this movement, to slide the idler wheel successively to smaller diameter steps of the drive roller. A rotary cam 32 is utilized in the change-speed mechanism for this purpose. This cam 32 is rotatably supported on the actuating shaft 31 and has on its face means for translating rotary movement of the cam into movement of the idler wheel axially of the stepped roller. In the present instance, the foregoing is accomplished by a horizontal pin 33 which engages the 60 end of the link 19 in a horizontal slot 34 provided

therein to receive the pin. The slot prevents binding due to the rotary movement of the pin. Upon turning the handle 30, the cam 32, through the agency of the pin 33, is effective to raise the floating mount for the idler wheel 15.

In addition to carrying out the vertical motion of the idler wheel, the rotary cam 32 presents on its face a series of notches 35a-e for cooperation with a pawl pin 36, providing a pawl and detent means for yieldingly holding the cam against movement from zero and drive positions, to establish precisely the proper level of the idler wheel with relation to the steps of the drive roller. Thus the cam has angular zero and drive positions corresponding to the zero and drive positions of the idler wheel. In the present instance, the pawl pin 36 is mounted adjacent the face of the rotary cam 32 by means of a rocker arm 37, which is formed as a U-shaped channel member having spaced plates 38, 39 pivotally mounted on the vertical pin 22 fixed to the player base. For normally urging the pawl pin 36 into engagement with the face of the cam 32 and into the notches 35a-e formed therein, the tension spring 40 is employed. It will be understood that the notches 35a-e are angularly so related as to establish the desired positions of the cam 32 and idler wheel mount.

As stated above, the cam 32 is rotatably supported on the actuating shaft 31. For turning the rotary cam 32, a disc 41 (Fig. 3) fixed to the actuating shaft 31 is employed. This disc includes a radially projecting arm portion 42 which is effective upon clockwise (Figure 1) rotation of the manual operating handle 30, to engage the pin 33 mounted on the face of the rotary cam for turning the cam about the shaft 31. A torsion spring 43 applies a resilient spring force resisting advance of the cam 32, and serves to hold the cam against the arm 42 as seen in Figure 1. A second torsion spring 44 applies a resilient spring force against the control handle 30, urging it in a clockwise direction as seen in Figure 1 toward the lower speed positions. In the mechanism illustrated in the figure, the torsion springs 43, 44 work in the opposite direction, against each other, and are substantially balanced. By means of the disc and offset arm 42, therefore, a direct coupling is established between the manually movable shaft 31, and the rotary cam 32, when the control handle 30 is turned in a clockwise direction. Normally, the click action due to the pawl 36 engaged in the notches 35a-e on the face of the cam 32, yieldingly holds the cam against accidental movement from the zero and drive positions, and also permits setting the idler wheel precisely by "feel" at the level of the stepped roller that will produce the desired turntable speed.

The second actuating means for the idler wheel mount in the present instance is effective to shift the idler wheel 15 laterally to clear the roller 13 upon movement of the control handle 30 toward the zero position. This control handle movement may start from any drive position and is transmitted by means of the disc 41, and radial arm portion 42, to the rocker arm 37 which engages and shifts the mount 17 so as to move the idler wheel laterally. Referring to Figs. 4 and 7, the radial arm portion 42 is shown in engagement with a tab 47 carried by the rocker arm 37 for pivoting the same. An ear 48 of arm 37 extending toward the idler wheel, is engageable, as shown in Fig. 7, with the rear surface of the link 19 for moving the idler wheel upon pivotal movement of the rocker arm away from the face of the rotary cam 32.

In accordance with the present invention, the idler wheel follows the movement of the control handle 30, in one direction of movement, to move from the zero position where it is spaced from the roller, into engagement with the larger roller step, and then to successive lower speed drive positions wherein the idler wheel is in engagement with successively smaller steps of the drive roller by sliding the idler wheel while in peripheral engagement with the roller and turntable in the direction of gradually decreasing roller step diameter.

Referring, for example, to the drawings, in the mechanism there depicted the idler wheel 15 is shown in Fig. 4 positioned at the zero position. Similarly, in Fig. 8, a plan view, the idler wheel is shown at the zero position. When in this zero position, the idler wheel 15 is at the level of the larger roller step, and spaced therefrom, and from the turntable 10.

Upon movement of the control handle 30 counter-clockwise from the solid line position in Fig. 4 (clockwise as viewed in Figure 1), the idler wheel mount is released to allow the idler wheel to move laterally from the zero position into engagement with the larger step of the pulley and the turntable flange under the urging of the tension spring 25. Successively as the pawl 36 or click allows it, the idler wheel 15 may be shifted into engagement with the smaller steps of the drive roller. As described above, the pawl pin 36 and the series of notches 35a-e borne by the rotary cam 32 provide a pawl and detent means, and the idler wheel 15 may be accurately positioned by feel at the level of an appropriate pulley step to obtain a given turntable speed. Thus the operator feels the successive movements of the idler wheel, the curved notches 35a-e presenting resistance to turning the control lever and enabling the operator to set the idler wheel precisely at the desired level. During the shifting of the idler wheel to the successive steps, the rocker arm 37 is oscillated about the fixed pin 22 due to a camming action between the edges of the notches 35a-e in the face of the cam and the pawl pin 36 sliding over these edges. The arrangement is such, however, that clearance is left between the rocker arm ear 48 and the link 19 so that no motion is transmitted to the link 19 and idler wheel, by virtue of this oscillating movement, while changing speeds.

For changing speed from a lower to a higher speed, in carrying out this invention, the idler wheel is first shifted directly from engagement with the drive roller, to the zero position; and then by movement of the control handle in the manner just described, the idler wheel is shifted to the step of the drive roller which will give the speed desired. For accomplishing the movement of the idler wheel to the zero position upon reverse movement of the handle, the second actuating means for the idler wheel mount is brought into operation. This means is effective to shift the idler wheel laterally to clear the drive roller, and simultaneously trips an idler wheel return mechanism by releasing the pawl and detent means. The idler wheel is shifted directly to the zero position by this return mechanism which is spring actuated independently of the manually controlled means.

This may best be seen by referring to Fig. 3, wherefrom it will be evident that forward (clockwise) movement of the control handle is transmitted by means of the disc 41, the radial arm portion 42 and the pin 33, to the rotary cam 32, which movement "winds up" the torsion spring 43. Upon reverse movement of the control handle 30, and the shaft 31, the rotary cam 32 remains stationary, being held in position by the click or pawl and detent means offered by the pawl pin 36 seated in the respective notch 35a-e. The tripping is caused when the rocker arm 37, moving as part of the second actuating means for the idler wheel mount referred to above, and effective to shift the idler wheel laterally to clear the drive roller, simultaneously moves the pawl pin 36 away from the face of the rotary cam 32, to release the pawl and detent means. Thereupon the energy stored in the wound-up spring 43 is utilized to move the rotary cam 32, the idler wheel mount, and idler wheel to the zero position.

Accordingly, by means of this invention, desired turntable speeds are obtained by a different action of the idler wheel than has been provided heretofore. A given turntable speed may be obtained by movement of the control handle from the zero position to the position corresponding to the desired speed. By movement of the control

handle in one direction from left to right or clockwise (in Figure 1), the idler wheel is shifted axially while retained in sliding engagement with the stepped roller, moving during this stage in the direction of gradually decreasing diameter roller steps. Upon reaching the smallest diameter roller step, or for that matter upon reaching any roller step, and reversal of movement of the control handle, the idler wheel is shifted laterally to clear the drive roller, and then displaced by spring means, acting independently of the control handle, directly to a declutched or zero position. In order to produce this return movement of the idler wheel to zero position, it has been necessary to place the control handle in a corresponding zero position, and thus the mechanism for controlling the idler wheel is re-engaged by the control handle for positioning the idler wheel in drive relation with the roller and turntable.

I claim as my invention:

1. In a phonograph apparatus having a record turntable, a stepped drive roller having a larger, high-speed step and successively smaller steps, and an idler wheel resiliently urged into driving relation between a flange on the turntable and the drive roller, a change-speed mechanism, said mechanism comprising, in combination, a floating mount for rotatably supporting the idler wheel, said mount being movable between a zero position wherein the idler wheel is spaced from the larger step of the roller and the turntable, and successive lower speed drive positions wherein the idler wheel is in engagement with successively smaller steps of the drive roller and the turntable, a cam for moving the idler wheel mount and having zero and drive positions corresponding to the zero and drive positions of the idler wheel, a spring urging said cam toward the zero position, pawl and cam carried detent means for yieldingly holding said cam against movement from the zero and drive positions, an actuating member mounted for movement between limits corresponding to the zero and low speed drive positions of the idler wheel, and operative upon movement to the zero position, to shift the idler wheel mount and move the idler wheel laterally to clear the roller, and to release said cam from said pawl, so that under the urging of said spring said cam and idler wheel are directly returned to the zero position, said actuating member being operative upon movement from the zero position, to release said idler wheel mount so that the idler wheel is resiliently urged into driving relation between the turntable and the larger step of the drive roller, said actuating member being operative upon continued movement from the zero position, by means of said cam, to shift the idler wheel vertically successively into engagement with the smaller steps of the roller.

2. In a phonograph apparatus having a record turntable, a stepped drive roller having a larger, high speed step and successively smaller steps, and an idler wheel resiliently urged into driving relation between a flange on the turntable and the drive roller, a change-speed mechanism, said mechanism comprising, in combination, a floating mount for rotatably supporting the idler wheel, said mount being movable between a zero position wherein the idler wheel is spaced from the larger step of the roller and the turntable, and successive lower speed drive positions wherein the idler wheel is in engagement with successively smaller steps of the drive roller and the turntable, a rotary cam for moving the idler wheel mount and having angular zero and drive positions corresponding to the zero and drive positions of the idler wheel, a spring urging said cam angularly toward the zero position, pawl and cam carried detent means for yieldingly holding said cam against angular movement from the zero and drive positions, an actuating member mounted for rotary movement between limits corresponding to the zero and low speed drive positions of the idler wheel, and operative upon movement to the zero position, to shift the idler wheel mount and move the idler wheel

laterally to clear the roller, and to release said cam from said pawl, so that under the urging of said spring said cam and idler wheel are directly returned to the zero position, said actuating member being operative upon movement from the zero position, to release said idler wheel mount so that the idler wheel is resiliently urged into driving relation between the turntable and the larger step of the drive roller, said actuating member being operative upon continued movement from the zero position, by means of said cam, to shift the idler wheel axially successively into engagement with the smaller steps of the roller.

3. In a phonograph apparatus having a record turntable, a stepped drive roller having a larger, high speed step and successively smaller steps, and an idler wheel resiliently urged into driving relation between the turntable and the drive roller, a change-speed mechanism, said mechanism comprising, in combination, a mount for rotatably supporting the idler wheel, said mount being movable between a zero position wherein the idler wheel is spaced from the larger step of the roller and the turntable, and successive lower speed drive positions wherein the idler wheel is in engagement with successively smaller steps of the drive roller and the turntable, spring means for urging said mount toward the zero position, means for yieldingly holding said mount against movement from the zero and drive positions, an actuating member mounted for movement between limits corresponding to the zero and low speed drive positions of the idler wheel, and operative upon movement from the zero position, by means of said mount, to shift the idler wheel from the zero position into engagement with the larger step of the roller and, upon continued movement, successively into engagement with the smaller steps of the roller, said actuating member being operative upon movement toward the zero position, to shift said idler wheel laterally and to release said mount so that under the urging of said spring means said mount and idler wheel are directly returned to the zero position.

4. In a phonograph apparatus having a record turntable, a stepped drive roller having a larger, high speed step, successively smaller steps, and an idler wheel resiliently urged into driving relation between the turntable and the drive roller, a change-speed mechanism, said mechanism comprising, in combination, a mount for rotatably supporting the idler wheel, said mount being movable between a zero position wherein the idler wheel is spaced from and at the level of the larger step of the roller and the turntable, and successive lower speed drive positions wherein the idler wheel is at the level of and in engagement with successively smaller steps of the drive roller and the turntable, spring means for urging said mount toward the zero position, means for yieldingly holding said mount against movement from the zero and drive positions, an actuating member mounted for movement between limits corresponding to the zero and low speed drive positions of the idler wheel, and operative upon movement from the zero position, by means of said mount, to shift the idler wheel into engagement with the larger step of the roller and, upon continued movement, axially thereof successively into engagement with the smaller steps of the roller, said actuating member being operative upon movement toward the zero position, to move said idler wheel laterally to clear the roller, and to release said mount so that under the urging of said spring means said mount and idler wheel are directly returned to the zero position.

5. In a phonograph apparatus having a record turntable, a stepped drive roller, and an idler wheel resiliently urged into driving relation between the turntable and the drive roller, a change-speed mechanism, said mechanism comprising, in combination, a mount for rotatably supporting the idler wheel, said mount being movable between a zero position wherein the idler wheel is spaced from the roller and turntable and drive posi-

tions wherein the idler wheel is in engagement therewith, spring means for urging said mount toward the zero position, means for yieldingly holding said mount against movement from the zero and drive positions, an actuating member mounted for movement between positions corresponding to the zero and drive positions of the idler wheel, and operative upon movement from the zero position, by means of said mount, to shift the idler wheel into engagement with the roller, said actuating member being operative upon movement toward the zero position, to release said mount, so that under the urging of said spring means said mount and idler wheel are directly returned to the zero position.

6. In a phonograph apparatus having a record turntable, a stepped drive roller having a larger high-speed step and successively smaller steps, and an idler wheel resiliently urged into driving relation between the turntable and the drive roller, a change-speed mechanism, said mechanism comprising, in combination, a mount for rotatably supporting the idler wheel, said mount being movable between a zero position wherein the idler wheel is spaced from the roller and turntable, and drive positions wherein the idler wheel is in engagement therewith, spring means for urging said mount toward the zero position, means for yieldingly holding said mount against movement from the zero and drive positions, an actuating member mounted for movement between positions corresponding to the zero and drive positions of the idler wheel, and operative upon movement from the zero position, by means of said mount, to shift the idler wheel into engagement with the larger step of the roller and axially thereof to the successively smaller steps by sliding the idler wheel while in peripheral engagement with the roller and turntable, said actuating member being operative upon movement toward the zero position, to shift said mount laterally to clear the idler wheel from the roller, and to release said mount, so that under the urging of said spring means said mount and idler wheel are directly returned to the zero position.

7. In a phonograph apparatus having a record turntable, a stepped drive roller having a larger, high-speed step and steps of successively smaller diameter to a low-speed step, and idler wheel resiliently urged into driving relation between a flange on the turntable and the drive roller, a change-speed mechanism, said mechanism comprising, in combination, a floating mount for rotatably supporting the idler wheel, said mount being movable between a zero position wherein the idler wheel is spaced from the roller and the turntable, to a high-speed and successive lower speed drive positions wherein the idler wheel is in engagement with successively smaller steps of the drive roller and the turntable, a cam for moving the idler wheel mount and having zero and drive positions corresponding to the zero and drive positions of the idler wheel, an actuating member mounted for movement independently of said cam between limits corresponding to the zero and low speed drive positions of the idler wheel, and operative upon movement from the zero position, to release the idler wheel so that the same is resiliently urged laterally into engagement with the larger step of the roller and, upon continued movement, by means of said cam, to the successively smaller steps of the roller by sliding the idler wheel axially while in peripheral engagement with the roller and turntable, and means for selectively returning said idler wheel to the zero position.

8. In a phonograph apparatus having a record turntable, a stepped drive roller having a larger, high-speed step and steps of successively smaller diameter to a low speed step, and an idler wheel resiliently urged into driving relation between a flange on the turntable and the drive roller, a change-speed mechanism, said mechanism comprising, in combination, a floating mount for rotatably supporting the idler wheel, said mount being

movable between a zero position wherein the idler wheel is spaced from the roller and the turntable, to a high-speed and successive lower speed drive positions wherein the idler wheel is in engagement with successively smaller steps of the drive roller and the turntable, a rotary cam for moving the idler wheel mount and having angular zero and drive positions corresponding to the zero and drive positions of the idler wheel, an actuating member mounted for rotary movement independently of said cam between limits corresponding to the zero and low speed drive positions of the idler wheel, and operative upon angular movement from the zero position, to release the idler wheel so that the same is resiliently urged laterally into engagement with the larger step of the roller and, upon continued movement, by means of said cam, to the successively smaller steps of the roller by sliding the idler wheel axially while in peripheral engagement with the roller and turntable, and means for selectively returning said idler wheel to the zero position.

9. In a multi-speed driving mechanism for phonographs of the type having a flanged turntable, the combination comprising: a stepped drive roller having a larger, high-speed step and steps of successively decreasing diameter to a smaller low-speed step; an idler wheel resiliently urged into driving relation between the turntable flange and the roller and having a zero position wherein the idler wheel is opposite the larger step of the roller and spaced from the same and the turntable flange, successive intermediate drive positions from high to low speed wherein the idler wheel is in engagement with the larger and the successively decreasing diameter steps of the roller, and a low speed drive position wherein the idler wheel is in engagement with the low speed step of the drive roller; an adjustable controller for said idler wheel comprising a manually operable actuating member movable in opposite directions between limits defining zero and low speed drive positions, respectively; means engageable with said idler wheel mount and operative upon movement of said member in one direction from the zero position to release the idler wheel so that the same is resiliently urged laterally into engagement with the larger roller step, and a cam coupled to said idler wheel mount and said actuating member and effective upon continued movement of said member in the same direction, to move said idler wheel axially from step to step of the roller by sliding the idler wheel while in peripheral engagement with the roller; a spring urging said cam in such direction as to return the idler wheel toward the zero position; click means for yieldingly holding said cam against movement from positions corresponding to the zero and drive positions of the idler wheel; and means for communicating movement of the actuating member in the reverse direction to said click means to release said cam, so that under the urging of said spring, said idler wheel is directly returned to the zero position.

10. In a multi-speed driving mechanism for phonographs of the type having a flanged turntable, the combination comprising: a stepped drive roller having a larger, high-speed step and steps of successively decreasing diameter to a smaller low speed step; an idler wheel resiliently urged into driving relation between the turntable flange and the roller and having a zero position wherein the idler wheel is opposite the larger step of the roller and spaced from the same and the turntable flange, successive intermediate drive positions from high to low speed wherein the idler wheel is in engagement with the larger and the successively decreasing diameter steps of the roller, and a low speed drive position, wherein the idler wheel is in engagement with the low speed step of the drive roller; an adjustable controller for said idler wheel comprising a manually operable actuating member rotatably mounted for movement in opposite directions between limits defining zero and low speed drive

positions, respectively; means engageable with said idler wheel mount and operative upon angular movement of said member in one rotary direction from the zero to the low speed position to release the idler wheel so that the same is resiliently urged laterally into engagement with the larger roller step, and a rotary cam coupled to said idler wheel mount and said actuating member and effective upon continued angular movement of said member in the same rotary direction, to move said idler wheel axially from step to step of the roller by sliding the idler wheel while in peripheral engagement with the roller; a spring urging said cam in such rotary direction as to return the idler wheel to the zero position; pawl and detent means for yieldingly holding said cam against angular movement from positions corresponding to the zero and drive positions of the idler wheel; and means for communicating movement of the actuating member in the reverse rotary direction to said idler wheel mount to shift the idler wheel laterally to clear the roller, and to said pawl and detent means to release said cam, so that under the urging of said spring, said idler wheel is directly returned to the zero position.

11. In a phonograph apparatus having a record turntable, a stepped drive roller having a larger, high-speed step and successively smaller steps to a low speed step, and an idler wheel resiliently urged toward driving relation between a flange on the turntable and the drive roller, a change-speed mechanism, said mechanism comprising, in combination, a floating mount for rotatably supporting the idler wheel, said mount being vertically and laterally movable between one limit zero position wherein the idler wheel is held opposite the larger step of the roller and spaced from the same and the turntable, and a second limit drive position wherein the idler wheel is resiliently urged into engagement with the low speed step of the drive roller, and having successive intermediate drive positions from high to low speed wherein the idler wheel is resiliently urged into engagement with the successively smaller steps of the roller, a cam for raising and lowering the idler wheel mount and having zero and drive positions corresponding to the zero and drive positions of the idler wheel, a spring urging said cam toward the zero position, pawl and detent means for yieldingly holding said cam against movement from the zero and drive positions, an actuating member mounted for movement in opposite directions between limits corresponding to the zero and low speed drive positions of the idler wheel, and operative upon movement in one direction from the zero position, to release the idler wheel for movement into resilient engagement with the larger step of the roller and, upon continued movement, to move the idler wheel, by means of said cam, into engagement with the successive smaller steps of the roller by sliding the idler wheel axially while in peripheral engagement with the roller and the turntable, said actuating member being operative upon movement in the reverse direction, to move said idler wheel laterally to clear the roller steps and to release said cam from said pawl and detent means, so that under the urging of said spring said cam and idler wheel are directly returned to the zero position.

12. In a phonograph apparatus having a record turntable, a stepped drive roller having a larger, high-speed step and successively smaller steps to a low speed step, and an idler wheel resiliently urged toward driving relation between a flange on the turntable and the drive roller, a change-speed mechanism, said mechanism comprising, in combination, a floating mount for rotatably supporting the idler wheel, said mount being vertically and laterally movable between one limit zero position wherein the idler wheel is held opposite the larger step of the roller and spaced from the same and the turntable, and a second limit drive position wherein the idler wheel is resiliently urged into engagement with the low speed step of the drive roller, and having successive intermediate drive positions from high to low speed wherein the idler

wheel is resiliently urged into engagement with the successively smaller steps of the roller, a rotary cam for raising and lowering the idler wheel mount and having angular zero and drive positions corresponding to the zero and drive positions of the idler wheel, a torsion spring urging said rotary cam angularly toward the zero position, pawl and detent means for yieldingly holding said cam against angular movement from the zero and drive positions, an actuating member mounted for rotary movement in opposite rotary directions between limits corresponding to the zero and low speed drive positions of the idler wheel, and operative upon movement in one rotary direction from the zero position, to release the idler wheel for movement into resilient engagement with the larger step of the roller and, upon continued movement in the same rotary direction, to move the idler wheel, by means of said cam, into engagement with the successive smaller steps of the roller by sliding the idler wheel axially while in peripheral engagement with the roller and the turntable, said actuating member being operative upon movement in the reverse rotary direction, to move said idler wheel laterally to clear the roller and to release said cam from said pawl and detent means, so that under the urging of said spring said cam and idler wheel are directly returned to the zero position.

13. In a phonograph apparatus having a record turntable mounted on a vertical axis, a stepped drive roller also mounted on a vertical axis and having a larger, high-speed step and successively smaller steps to a low speed step, and an idler wheel resiliently urged into driving relation between a flange on the turntable and the drive roller, a change-speed mechanism, said mechanism comprising, in combination, a floating mount for rotatably supporting the idler wheel, said mount being vertically and laterally movable between one limit zero position wherein the idler wheel is opposite the larger step of the roller and spaced from the same and the turntable, and a second limit drive position wherein the idler wheel is in engagement with the low speed step of the drive roller, and having successive intermediate drive positions from high to low speed wherein the idler wheel is in engagement with the successively decreasing diameter steps of the roller, a cam for raising and lowering the idler wheel mount and having zero and drive positions corresponding to the zero and drive positions of the idler wheel, a spring urging said cam toward the zero position, an actuating member mounted for movement in opposite directions between limits corresponding to the zero and low speed drive positions of the idler wheel, and effective upon movement in one direction from the zero position, to release the idler wheel so that the same moves laterally into resilient engagement with the larger step of the roller, means coupling said cam to said actuating member so that upon continued movement of the actuating member in the same direction said cam is effective to move the idler wheel to the successively smaller steps of the roller by sliding the idler wheel axially while in peripheral engagement with the roller and the turntable, said actuating member being effective upon movement in the reverse direction to shift said idler wheel laterally toward the zero position and to release said cam so that under the urging of said spring, the idler wheel is returned directly to the zero position.

14. In a phonograph apparatus having a record turntable mounted on a vertical axis, a stepped drive roller also mounted on a vertical axis and having a larger, high-speed step and successively smaller steps to a low speed step, and an idler wheel resiliently urged into driving relation between a flange on the turntable and the drive roller, a change-speed mechanism, said mechanism comprising, in combination, a floating mount for rotatably supporting the idler wheel, said mount being vertically and laterally movable between one limit zero position wherein the idler wheel is opposite the larger step of the roller and spaced from the same and the turntable, and a second

limit drive position wherein the idler wheel is in engagement with the low speed step of the drive roller, and having successive intermediate drive positions from high to low speed wherein the idler wheel is in engagement with the successively decreasing diameter steps of the roller, a rotary cam for raising and lowering the idler wheel mount and having angular zero and drive positions corresponding to the zero and drive positions of the idler wheel, a spring urging said cam angularly toward the zero position, an actuating member mounted for movement in opposite directions between limits corresponding to the zero and low speed drive positions of the idler wheel, and effective upon movement in one direction from the zero position, to release the idler wheel so that the same moves laterally into engagement with the larger step of the roller, means coupling said cam to said actuating member so that upon continued movement of the actuating member in the same direction said cam is effective to move the idler wheel vertically to the successively smaller steps of the roller by sliding the idler wheel while in peripheral engagement with the roller and the turntable, means connecting said actuating member and said idler wheel mount so that upon movement of the actuating member in the reverse direction said idler wheel is shifted laterally to clear the roller, and said cam under the urging of said spring is effective to return the idler wheel vertically to the zero position.

15. In a phonograph apparatus having a record turntable, a stepped drive roller, and an idler wheel resiliently urged into driving relation between the turntable and the drive roller, a change-speed mechanism, said mechanism comprising in combination, a floating mount for rotatably supporting the idler wheel, said mount being vertically and laterally movable between a zero position wherein the idler wheel is opposite the larger step of the roller and spaced from the same and the turntable, and drive positions wherein the idler wheel is in engagement with the drive roller and the turntable, a manually operable controller for said mechanism including a shaft mounted for rotary movement adjacent said idler wheel mount and having a control handle, a rotary cam for moving the idler wheel mount and rotatably mounted on said shaft for independent movement, said cam including a cam face opposite said mount, means on said cam face for translating rotary movement of said cam to vertical movement of said mount, said cam having angular positions corresponding to the zero and drive positions of the idler wheel, a torsion spring rotatably urging said cam in one angular direction toward the zero position, a rocker arm pivotally mounted adjacent the face of said cam and engageable with the idler wheel mount, a pawl on said rocker arm, said cam face having a succession of detents for cooperation with said pawl for yieldingly holding said cam against angular movement from the zero and drive positions, a disc mounted on said shaft and having an arm engageable to shift said rocker arm in a direction to engage the idler wheel mount and move the idler wheel to the zero position thereof as an incident to movement of the control handle to the zero position, said arm being

operable upon movement of the control handle from the zero position to separate said rocker arm from engagement with the idler wheel mount to release the idler wheel so that the same moves laterally into resilient drive relation between the larger step of the roller and the turntable, said cam being effective upon continued movement of the control handle from the zero position to shift the idler wheel into engagement with the successively smaller steps of the roller by sliding the idler wheel axially while in peripheral engagement with the roller and the turntable, said arm being effective upon movement of the control handle toward the zero position to pivot said rocker arm in a direction away from the face of the rotary cam whereby to release said cam from said pawl, so that under the urging of said spring said cam is rotated to the zero position thereby to return said idler wheel to the zero position.

16. In a phonograph apparatus having a record turntable, a stepped drive roller, and an idler wheel movable into driving relation between the turntable and the drive roller, a change-speed mechanism, said mechanism comprising, in combination, means mounting the idler wheel and roller for relative lateral and axial movement, said means being actuatable between a first position wherein the idler wheel is adjacent the largest roller step and successive positions wherein the idler wheel is adjacent the successively smaller steps of the roller, a spring tending to draw the idler wheel into engagement with the roller and the turntable for establishing driving relation therebetween, an actuating member selectively movable between positions corresponding to said first and said successive positions, cam means operated by said actuating member and connected with the means mounting the idler wheel and roller, said cam means being constructed and arranged to slide the roller and the idler wheel relatively axially while the same remain in peripheral engagement in the direction from the larger to the smaller steps, yieldable means for holding the idler wheel and roller against movement relative to each other from said positions, means connected to said actuating member for shifting the idler wheel laterally to clear the roller steps upon movement of the member toward the said first position and coincidentally to release the idler wheel and roller from said yieldable means, and spring means effective upon such release for shifting the roller and idler wheel relatively axially to the first position.
